CLAIM

The ornamental design for a trailer cover, as shown and described.

DESCRIPTION

FIG. 1 is a perspective view of a trailer cover showing my new design;

FIG. 2 is a left side elevational view thereof with the right side being a mirror image;

FIG. 3 is a top plan view thereof;

FIG. 4 is a front elevational view thereof;

FIG. 5 is a rear elevational view thereof; and,

FIG. 6 is a bottom plan view.

The broken lines shown in FIG. 1 are for illustrative purposes only and form no part of the claimed design.
